UNITED STATES PATENT OFFICE.

FRANK R. CUNNINGHAM, OF MEDFORD, MASSACHUSETTS, ASSIGNOR TO
BIGELOW, KENNARD & CO., OF BOSTON, MASSACHUSETTS, A FIRM.

HAIR-SPRING COLLET FOR TIMEPIECES.

SPECIFICATION forming part of Letters Patent No. 783,621, dated February 28, 1905.

Application filed June 9, 1904. Serial No. 211,850.

To all whom it may concern

Be it known that I, FRANK R. CUNNINGHAM, a citizen of the United States, residing at Medford, in the county of Middlesex and State of 5 Massachusetts, have invented certain new and useful Improvements in Hair-Spring Collets for Timepieces, of which the following is a specification.

In watches and other timepieces as heretofore constructed the inner end of the hair-spring has been secured within a round hole extending in a straight line through the collet by means of a flattened taper pin. This method is objectionable for the reason that 15 the end of the spring requires to be bent abruptly at an angle in order to properly enter the hole in the collet, said sharp bend not only being injurious to the spring, but also exerting a disturbing influence on the uniform progression of tension of the spring during the vibrations.

My invention has for its object to overcome these difficulties and to provide a more perfect means of attaching the hair-spring to the 25 collet.

With this end in view my invention consists in certain other novel features and details of construction, as hereinafter described and claimed.

30 In the accompanying drawings, Figure 1 is an enlarged plan view of my hair-spring collet and part of the hair-spring which is connected therewith. Fig. 2 is a vertical section of the collet on the line 2 2 of Fig. 1. Fig. 3 is a plan view of the lower part of the collet, showing the groove for holding the inner end of the hair-spring.

In the said drawings, A represents a collet which is secured in the usual manner to the 40 balance-staff, (not shown,) which passes friction-tight through the hole b. The collet is composed of two pieces 10 12, Fig. 2, connected together by a screw a and a steady-pin

c. Each of the pieces 10 12 is provided on its inner or meeting face with a curved groove 45 g, forming when the two pieces are placed together a recess for the reception of the inner end of the hair-spring e. The walls of the grooves g are preferably tapered, as shown in Fig. 2, whereby the spring is fastened tightly 50 in place when the two parts of the collet are secured together by the screw a.

By forming the collet in two pieces and securing the spring in a recess or groove formed between the same as described I am enabled 55 to secure a uniform progression of tension of the spring in its vibrations and also to vary the character of the alternate vibrations as may be necessary. Furthermore, with my construction I avoid the transverse buckling 60 of the inner end portion of the hair-spring which has heretofore been produced by wedging the said end of the spring within a round hole in the collet and which is objectionable 65 on account of its injury to the spring and its disturbing influence on the uniformity of its vibrations.

What I claim as my invention, and desire to secure by Letters Patent, is—

1. A hair-spring collet composed of two 70 pieces secured together and having formed in each of their inner faces a groove for receiving and holding the inner end of the hair-spring.

2. A hair-spring collet composed of two 75 pieces secured together and having formed in each of their inner faces a groove for receiving and holding the inner end of the hair-spring; said grooves tapering in a direction perpendicular to the plane of the balance. 80

Witness my hand this 3d day of June, A. D. 1904.

FRANK R. CUNNINGHAM.
